(57) **CLAIM**

The ornamental design for a vanity mirror with bluetooth speakerphone, as shown and described.

DESCRIPTION

FIG. 1 is a top, front perspective view of a vanity mirror with bluetooth speakerphone showing my new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a cross-sectional view taken along and in the direction of line 8-8 of FIG. 2.

The broken lines and the areas depicting the interior of the article, as shown in FIG. 8, represent portions of the vanity mirror with bluetooth speakerphone that form no part of the claimed design.
